[57] **ABSTRACT**

The method applicable both to the execution of button-holes and to the execution of pocket-openings primarily consists in pre-forming the opening with turned-in edges in the bottom piece, in turning-in a braid and inserting said braid together with an auxiliary piece beneath the opening of the bottom piece, in fastening said braid and said auxiliary piece along one edge and at both ends of the pre-formed opening, and also in fastening the other edge of the opening of the bottom piece onto an auxiliary piece.

METHOD OF FORMING BRAIDED ELONGATED OPENINGS

This invention relates to the clothing industry and more particularly to the formation of braided elongated openings in pieces of material in the form of sheets such as woven or non-woven fabrics, knitted material or else sheets of thermoplastic material, by means of fastening lines formed in any manner which is suited to the application considered such as, for example, sewing, bonding or gluing.

The invention will be described more particularly insofar as concerns its application to the formation of button-holes and trousers pockets.

The execution of braided button-holes usually calls for a relatively large number of operations. In the case of a button-hole having two braids, for example, it was necessary to begin on a two-needle sewing machine by applying against the base fabric a piece of cloth (with an internal strengthening-piece if necessary) which is intended to form the two braids, then to cut a recess having the shape of a double "Y" in said opening in order to separate the braids and, in a so-called turning operation, to insert the braids through the opening. The first two operations were carried out either by hand or automatically in the cycle of the machine which was accordingly designed for this purpose. It then remained necessary to fasten-off at the ends of the opening either on an ordinary machine or on an automatic machine, to add the complementary piece (facing), to cut a recess in the shape of a double "Y" in said piece and to carry out a surface finish by ironing by hand.

In order to make a trousers pocket having a braided opening, the usual procedure was similar to the method adopted for the formation of button-holes.

The invention is directed to a method which does not only entail a smaller number of operations but can above all be easily carried out by automatic means which permit of incorporation in a mass-production cycle.

To this end, the method according to the invention, which is applicable both to the execution of button-holes and to the execution of pocket-openings primarily consists in pre-forming the opening with turned-in edges in the bottom piece, in turning-in a braid and inserting said braid together with an auxiliary piece beneath the opening of the bottom piece, in fastening said braid and said auxiliary piece along one edge and at both ends of the pre-formed opening, and also in fastening the other edge of the opening of the bottom piece onto an auxiliary piece.

By virtue of this method, all the operations involved in forming the opening can be carried out in a flat position, the different pieces being located during the entire operation in the final relative positions which they will occupy in the finished article of clothing. This novel method permits a reduction in the number of operations entailed in the formation of the button-hole since there is no longer any cutting operation to be performed with scissors, since there is no longer any need for fastening-off at the ends of the opening by reason of the fact that fastening-off operations are incorporated in the stitching cycle, and since there is no longer any need to perform a final ironing operation. Moreover, the general appearance of the button-hole is improved by the fact that it has neater edges, that there is better flattening of overthicknesses without any at-

tendant danger of deformation. Finally, it can be stated that, in general, the method proposed permits a saving of time and stabilization of the work resulting from much more extensive automation.

5 The lines of fastening of the different pieces can be formed, for example, by seams sewn with running stitches but it is an advantage to form them on zigzagging sewing machines since they are in that case practically invisible.

10 The invention is also directed to a unit for the practical application of this novel method. The unit according to the invention is characterized in that, for the execution of seams of the above-mentioned type or the like along a path formed by a succession of straight-line seg-

15 ments inclined at an angle to each other, said unit comprises: a turntable for supporting the pieces to be assembled; means whereby said supporting turntable can be secured at will in a number of predetermined angular positions in its own plane to a guide which is movable in a rectilineal slide parallel to the line of action aforesaid; means for imparting movements of displacement in both directions to the guide which is movable within the slide; and means whereby the supporting turntable can be pivotally displaced through a prede-

20 termined angle with respect to the movable guide within the slide.

25 By virtue of this particular structural design, the path followed by the pieces along the line of action of the machine, that is to say, beneath the needle of a sewing machine, is accurately determined by the slide and by the angular position which is given to the supporting turntable with respect to the movable guide within said slide for the execution of each portion of seam. The general configuration of the complete

30 seam is wholly determined by mechanical components and can therefore be maintained with a high degree of accuracy, the seam being made rapidly and consequently at low cost.

35 In a particular form of execution, the unit which comprises a sewing machine for stitching braided pockets is characterized in that the supporting turntable is made up of four sub-assemblies, namely as follows:

40 A cradle comprising an upper plate and a lower plate joined together by means of small columns;

45 A removable frame for supporting the bottom piece of material, said frame being locked to the upper cradle-plate and made up of two holding-plates pivoted about a hinge; and

50 Two removable drawers in superposed relation which enclose the pocket half-bags and are housed within compartments between the frame and the upper cradle-plate.

55 Although this machine has been specially designed for fastening pieces of textile fabric, its field of application is not limited to the clothing industry. On the contrary, the principle of the machine could be applied to many other types of work. By way of example, it follows from this that the lines of fastening of pieces need not necessarily form rectangles but could equally well be polygonal or have any other configuration and, in a more general manner, could conform to any zig-zag line arrangement. Moreover, the worked material need not consist of a textile fabric (woven, non-woven or knitted) but could consist, for example, of a sheet of thermoplastic material or any other material in sheet form, depending on the applications which may be contemplated. The sheets themselves need not necessarily

be flexible but could, on the contrary, be rigid sheets.

Finally, the invention is concerned with pieces which are worked in accordance with the method and/or in a unit as claimed in this patent.

A better understanding of the invention will be gained from the following description and from a study of the accompanying drawings which show by way of example two machines for the formation of trousers pockets having braided openings and for the formation of braided button-holes respectively, the operation of which reproduces the successive operations of the method according to the invention.

In these drawings:

FIG. 1 is a front view of a machine according to the invention for making trousers pockets having braided openings;

FIG. 2 is a profile view of the upper main portion of the machine, looking in the direction of the arrow II in FIG. 1;

FIG. 3 is a plan view corresponding to FIG. 2, the sewing machine being assumed to have been removed;

FIG. 4 is a sectional view to a larger scale showing the detail of the frame and the drawers in the position in which they may be seen in FIG. 2;

FIG. 5 is a plan view to a larger scale showing the system for locking the frame which appears in FIG. 3;

FIG. 6 is a sectional view taken along line VI—VI of FIG. 5;

FIG. 7 is a sectional view taken along line VII—VII of FIG. 5;

FIG. 8 is a plan view to a larger scale showing the frame-carrier assembly and presser foot which appear in FIG. 3;

FIG. 9 is a sectional view taken along line IX—IX of FIG. 8;

FIG. 10 is a vertical sectional view showing the pivotal-motion system of the frame in the work position of FIG. 1;

FIG. 11 is a plan view corresponding to FIG. 10;

FIG. 12 is a view which is similar to FIG. 10 and shows the same device in a position of pivotal motion;

FIG. 13 is a profile view to a larger scale showing the system for controlling the pivotal motion of the frame as already shown in FIG. 2;

FIG. 14 is a separate plan view of the frame-supporting plate in the same position as in FIG. 3;

FIG. 15 illustrates to a larger scale a portion of the transmission system for controlling the forward motion of the frame, as represented only diagrammatically in FIG. 1;

FIG. 16 is a sectional view taken along line XVI—XVI of FIG. 15;

FIG. 17 is a sectional view to a larger scale and taken along line XVII—XVII of FIG. 1;

FIG. 18 is a view to a larger scale showing the coupling system for the frame-displacement control mechanism, as can be seen from FIG. 1;

FIG. 19 is a plan view of the drawer for the outer half-bag of a pocket;

FIGS. 20 and 21 are sectional views taken respectively along lines XX—XX and XXI—XXI of FIG. 19;

FIG. 22 is a plan view of the drawer for the inner half-bag of a pocket;

FIGS. 23 and 24 are sectional views taken respectively along lines XXIII—XXIII and XXIV—XXIV of FIG. 22;

FIG. 25 shows the incision in the shape of a double Y for preparing the pocket opening in the bottom fabric;

FIG. 26 shows the turned-in opening;

FIG. 27 is a sectional view to a larger scale and taken along line XXVII—XXVII of FIG. 26;

FIG. 28 shows the outer pocket half-bag fitted with its braid;

FIG. 29 shows the inner pocket half-bag fitted with its pocket bottom;

FIGS. 30 to 33 illustrate in section the successive stages of preparation of the pocket;

FIG. 34 shows in section the completed pocket on the trousers;

FIGS. 35 to 37 are front views illustrating the successive stages of fabrication of the pocket on the trousers;

FIG. 38 is a front view showing the appearance of the pocket opening which is sewn in running stitches;

FIGS. 39 and 40 show respectively in a front view and in a sectional view, the appearance of the pocket opening which is sewn in zig-zag stitches;

FIG. 41 is a sectional view showing the preparation of the opening in the bottom fabric and in the facing-piece for the formation of button-holes;

FIG. 42 is a plan view corresponding to FIG. 41;

FIG. 43 shows the preparation of a braid;

FIG. 44 illustrates the button-hole with one completed braid;

FIG. 45, which shows the preparation of a button-hole with two braids, is identical with FIG. 41;

FIG. 46 shows the preparation of the two braids;

FIG. 47 shows the completed button-hole with two braids;

FIG. 48 shows in perspective a sewing machine for making braided button-holes by means of the method according to the invention;

FIG. 49 is a sectional view showing a pocket with an opening having one braid and a flap;

FIG. 50 is another sectional view showing a pocket with an opening having two braids and a flap.

The sewing unit which is shown generally in FIGS. 1 to 3 is essentially made up of a frame 1 on which are mounted a sewing machine 2 and a cradle 4 so designed and arranged as to be capable of supporting the pieces to be assembled by sewing, within the sewing machine, and of displacing said pieces at will in the different directions along which the seams are to be made.

The sewing machine 2 is preferably of the zig-zag stitch type and does not have a toothed feed component for the displacement of pieces to be sewn since these latter are moved forward positively by external means for displacing the cradle 4 successively in each desired direction and orientation and at the appropriate rate of feed, beneath the needle 5 of the sewing machine which is driven by means of a belt 6 from an electric motor 3.

The presser foot 11 is of special design (as shown also in FIGS. 4, 8 and 9). Said foot is constituted by a rectangular plate 12 having an opening and carried by two arms 13, 14 rigidly fixed to a horizontal tube 15 which is in turn secured in overhung position to a shaft 16 pivotally mounted in a needle-bearing 17 rigidly fixed to

a support 18 which is attached to the cradle 4, as will be explained hereinafter.

The plate 12 of the presser foot is connected to the extremity of each of the two arms 13 and 14 by means of an elastic coupling comprising a screw 31 (shown in FIG. 9) which is mounted in the extremity of each arm, a universal joint constituted by a spherical bearing 32 which is capable of sliding on the smooth shank of the screw 31 and a ring 33 which is rigidly fixed to the corresponding extremity of the open plate 12 and constitutes the body of the spherical bearing whilst a helical compression spring 34 is interposed between the extremity of said arm and said bearing.

The dimensions of the opening 19 formed in the plate 12 of the presser foot correspond to the area of the zone in which seams are to be made in the pieces to be assembled, with provision for a margin of a few millimeters in order to reduce the danger of breakage of the needle.

The mechanism for controlling the lifting and lowering movement of the presser foot consists of a pressurized-fluid jack 23 (shown in FIG. 3) which is also carried by the cradle 4 and the moving element of which is connected to an arm 24 fixed on the outer extremity of the shaft 16.

The cradle 4 is essentially composed of a lower plate 37 and an upper plate 38 which are connected together only by means of three small columns 41, 42, 43 in order that they may be displaced together in pivotal motion through an angle of 90° about a vertical axis which coincides with the axis of the needle 5 of the sewing machine in such manner that said small columns should not strike any components during these movements. The undersurface of the upper cradle-plate 38 is located at exactly the same level as the surface of the table 44 of the sewing machine.

The shaft which carries the presser foot 12 is rotatably mounted in a bearing 17 supported by a bracket 18 which is fixed on the small column 41 by means of a collar 45 (as shown in FIG. 8).

The lower cradle-plate 37 rests on shoes such as ball-mounted shoes 46, for example, (as shown in FIGS. 1 and 2) which are fixed on a table 51 forming part of the frame 1 of the unit. Said cradle-plate can be rigidly fixed in a number of different relative positions to a horizontal rectilineal guide 53 (shown in FIGS. 1, 2 and 10 to 13), said guide being capable of moving within a ball-mounted slide 55, the center of which is located vertically beneath the needle 5 of the sewing machine and which is capable of displacement to a slight extent in the vertical direction. To this end, said slide is fixed on the lower extremities of two vertical rods 56, 57 which are capable of sliding within two corresponding vertical tubular guides 58, 59, said guides being secured to a bracket 62 which is fixed on the extremity of a rigid arm 63 forming part of the frame 1. The slide 55 is urged elastically downwards by a helical compression spring 66 placed around a central rod 67 and interposed between said slide and a plate 68 which connects the lower ends of two tubular guides 58, 59.

The lower cradle-plate 37 can be rigidly fixed to the rectilineal guide 53 by means of two guiding studs 72, 73 which project from the underface of said guide and are capable of engaging respectively in corresponding pairs of holes 74A, 75A (see also FIG. 14) or 74B, 75B or 74C, 75C, or 74D, 75D, depending on the relative

positions taken up by the cradle-plate 37 with respect to the guide 53.

The cradle-plate 37 can be caused to pivot in its plane by means of a device comprising a fork 81 (as shown in FIGS. 10 and 12) having a central tooth 82 and two lateral teeth 83, said fork being fixed on the upper extremity of a vertical shaft 85 which is rigidly fixed to the movable portion of a rotational-motion control jack 86, the other portion of which is supported by the piston rod 88 (FIG. 13) of a jack 89 having a rectilineal travel, the cylinder 92 of which is carried by a bracket 93 which is rigidly fixed to the frame 1. By means of this combination of the two jacks, the fork 81 can either be raised and lowered or caused to pivot through one-quarter of a revolution either in one direction or in the other about a vertical axis which coincides with the axis of the needle 5 of the sewing machine.

The two lateral teeth 83 of the fork are intended to engage in pairs of holes such as 101Aa, 101Ab, 101Ba, 101Bb, 101Ca, 101Cb, 101Da or else 101Db (as shown in FIG. 14).

The central tooth 82 of the fork 81, which is slightly longer than the two lateral teeth 83, is intended to lift the guide 53 through intermediate holes such as 102Ca, 102Cb, 102Da, or 102Db. In order that said guide should not be liable to be displaced with respect to the central tooth 82 of the fork, the conical extremity of said tooth engages to a slight extent within one of a series of corresponding holes such as the hole 104 (shown in FIG. 10) of said guide.

In order that the pivotal motion of the cradle-plate 37 with respect to the movable guide 53 should be initiated by means of the jack 89, the fork 81 is lifted, the central tooth 82 of said fork passes through a hole such as 102Ca of the cradle-plate 37 and engages in a hole 104 of the movable guide 53 which is lifted by said tooth to a sufficient extent to ensure that the two lugs 72, 73 are withdrawn from the holes 74A, 75A of the cradle-plate in which they were previously engaged (as shown in FIG. 12). During this movement, the slide 55 and the components which are secured thereto are moved upwards over the same distance while compressing the spring 66. At the same time, the two lateral teeth 83 of the fork have engaged in the holes such as 101Aa of the cradle-plate. In consequence, it is now possible by means of the jack 86 to cause said fork to pivot through one-quarter of a revolution, thereby initiating a corresponding pivotal motion of the cradle-plate 37 and the complete cradle unit 4 which is rigidly fixed thereto about the vertical geometrical axis of the needle 5 of the sewing machine. By means of the jack 89, the entire moving system is moved downwards again, with the result that the fork is withdrawn from the movable guide 53 and from the cradle-plate 37 whilst the two lugs 72, 73 of said guide engage, for example, in the holes 74C and 75C of the cradle-plate 37 which will now be able to move once again in the direction of the slide but will be located in an angular position which is displaced in its own plane through an angle of 90°.

In order to prevent any danger of lifting of the cradle-plate 37 at the time of upward motion of the fork 81, provision has been made for a ball stop 106 which is tangent to the top face of said cradle-plate and carried by an arm 107 which is rigidly fixed to the stationary

bracket 62 (as shown in FIGS. 2 and 13). A number of similar stops could also be mounted.

The cradle-plate 37 can be displaced along the slide 55 by means of a rod 112 (shown in FIG. 18) which is slidably mounted in a stationary tubular support 113. There is fixed on one extremity of said rod a tongue 114 for supporting a pressurized-fluid jack or an electromagnet 115, the moving element of which carries a coupling stud 116, said stud being capable of engagement within a hole such as 118A, 118B, 118C or 118D of the cradle-plate 37 (as shown in FIG. 14). During the pivotal movements of the cradle-plate, the stud 116 is evidently withdrawn so as to release the cradle-plate.

The sliding rod 112 can be driven from the main shaft 113 (shown in FIG. 2) of the sewing machine 2 by means of a transmission system which essentially comprises: a rack 121 (shown in FIG. 18) which is integral with the rod 112, a toothed pinion 122 disposed in meshing engagement with the rack 121 and keyed on the output shaft 123 of a feed control box 124 (shown in FIGS. 1 to 3), an oscillating lever 125 for the transmission of motion into said box, a connecting-rod 126, a crank-arm 127 rigidly fixed to a shaft 128 rotatably mounted in two bearings 129 which are fixed on the frame 1, and a slotted belt 132 passed over a pulley 133 which is keyed on the shaft 128 (as shown especially in FIG. 2) and over a pulley 134 which is keyed on the shaft 113 of the sewing machine.

The feed control box 124 comprises an input shaft 141 (shown in FIG. 17) which is rotatably mounted in two bearings 142, 143 and carries a forward-motion driving pinion 144 and a reverse-motion driving pinion 145. The pinion 144 is directly in mesh with another pinion 146 having the same diameter and rigidly fixed to a disc 147 which is mounted to rotate freely on the output shaft 123 of the box. Said disc forms part of a first magnetic clutch unit which is generally designated by the reference 148 and comprises another disc 149 which is made fast for rotation with the output shaft 123 and intended to cooperate with the disc 147. The reverse-motion driving pinion 145 is smaller in diameter than the forward-motion driving pinion 144 and carried by the input shaft 141. Said pinion 145 is connected by means of a motion-reversal pinion 152 carried by a stationary pin 153 to another pinion 154 having the same diameter as the pinion 145 and rigidly fixed to a disc 155 which is also mounted to rotate freely on the output shaft 123 of the box. Said disc forms part of another electromagnetic clutch unit 157 in which the other disc 158 is made fast for rotation with said shaft 123. The two bearings in which the output shaft 123 are rotatably mounted are shown at 161 and 162.

In the example which is illustrated, the box 124 is essentially constituted by two end-plates 165, 166 connected together by means of spacer rods 167.

The lever 125 for transmission of motion into the feed control box 124 is rigidly fixed to the outer ring 171 of a free wheel of any suitable and conventional type, for example of the type comprising cylindrical rollers 172 in cooperating relation with ramps, the inner member 173 of said free wheel being rigidly fixed to the input shaft 141 by means of a key 175, for example.

There is shown in greater detail in FIG. 15 the connecting-rod 126, one extremity of which is pivotally at-

tached by means of a pin 181 to a split collar 182 which can be clamped by means of a screw 183 in any desired position on the rod 125 in order to permit the possibility of adjusting the amplitude of the angular movement of oscillation of said rod.

The other extremity of the rod 126 is rigidly fixed to a sleeve 186 (as also shown in FIG. 16) which is rotatably mounted on the crank-arm 127 carried by the shaft 128. The radius of said crank-arm can be adjusted at will since this latter is integral with a nut 187 which is engaged on a radial-direction screw 188 mounted in a casing 189, said casing being fixed on the shaft 128 by means of a locking-pin 191 for example. By rotating the screw 188 either in one direction or in the other, the nut 187 is displaced with respect to the axis of the shaft 128, with the result that the effective radius of the crank-arm 127 is accordingly varied to the same extent.

In the case of a given speed of the main shaft 113 of the sewing machine, and if neither of the two electromagnetic clutch units 148, 157 is engaged, the output shaft 123 of the feed control box 124 does not rotate, with the result that the pinion 122 (shown in FIGS. 17 and 18) and the rack 121 are motionless and that the rod 112 and the cradle-plate 37 are consequently also motionless. Depending on whether one or the other clutch unit aforesaid is brought into engagement, the step-by-step forward motion of the cradle-plate 37 is effected either in one direction or in the other, in synchronism with the upward and downward movements of the needle of the sewing machine, the displacements of the cradle-plate being carried out during the periods in which the needle is in the top position. The amplitude of forward movements can conveniently be regulated by adjusting the position of the collar 182 on the rod 125 and the radius of the crank-arm 127.

The upper cradle-plate 38 rests on the upper extremities of the three small columns 41, 42, 43 (as shown in FIGS. 1 to 3, 4 and 7). A lower holding-plate 201 (shown in FIGS. 4 and 6) is fixed on top of said cradle-plate 38 by means of battens 202, 203, 204, 205 in such manner as to leave a small space between the top face of the cradle-plate 38 and the underface of the lower holding-plate 201. The corresponding edge of an upper holding-plate 208 is pivotally mounted on one edge of the lower holding-plate 201 by means of a hinge 207.

In the example considered, the machine is designed for the successive sewing of an outer half-bag and an inner half-bag on the edges of a turned-in opening of the bottom fabric of a pair of trousers. The bottom piece of material or fabric will be placed between the two holding-plates 201 and 208, and turned-in opening of said piece of material being suitably positioned with respect to two openings 211, 212 which are formed respectively in said two holding-plates. The upper cradle-plate 38 is also provided with a corresponding opening 213. These openings are of sufficient size to permit a wide field of action for the presser foot.

For the sake of convenience of handling operations, those edges of the two holding-plates which are remote from the hinge 207 are raised in the form of handles 216, 217. Thus, that part of the trouser-leg which might interfere with stitching operations can be rolled-up between these two handles.

Within the space which is formed between the cradle-plate 38 and the lower holding-plate 201, there can

successively be inserted a lower drawer 221 which will be referred-to hereinafter as the inner drawer since this latter is intended to receive the inner pocket half-bag and an upper drawer 222 which will be designated hereinafter as the outer drawer since this latter is intended to accomodate the outer pocket half-bag.

The inner drawer and the outer drawer are of similar constructional design. The inner drawer 221, for example, is formed of a first rectangular sheet-metal plate 235 (shown in FIGS. 22 to 24) having a thickness of the order of 0.5 mm, for example. There are fixed on said plate a heel element 226 and two side elements 227 having a thickness of the order of 1 mm, for example. A rectangular plate 228 having a thickness of the order of 0.5 mm, for example, can be freely inserted in the rectangular space which is delimited by the edges of the heel element 226 and the two side elements 227. The inner pocket half-bag can be imprisoned between the bottom plate 225 and the cover 228. The bottom and the cover are provided with a wide recess 229 in the zone of the stitches to be made.

The outer drawer 222 (shown in FIGS. 19 to 21) is similarly constituted by a bottom 232, a heel element 233, two side elements 234 and a cover 235; the outer pocket half-bag can be imprisoned between the bottom and the cover. The recess 236 formed in the bottom and in the cover has a smaller depth than the recess of the inner cover for reasons which will be explained hereinafter.

The outer extremity of the outer drawer 222 has a hole 237 and the outer extremity of the inner drawer 221 is provided with two holes 238, 239; this makes it possible by means of a dowel-pin, for example, to set the two drawers in two different and precise relative longitudinal positions at the time of sewing of the two inner and outer half-bags respectively.

The intended function of the presser foot 11 is to apply the pieces to be stitched against the table 44 of the sewing machine 2 through the openings of the two holding-plates 201, 208, of the two drawers 221, 222, and of the upper cradle-plate 38.

The assembly which is constituted by the upper cradle-plate 38 and the two holding-plates 201, 208 can be accurately positioned and maintained on the small columns 41, 42, 43 (shown in FIGS. 1 to 8) by means of a locking system comprising two conical studs 242, 243 which engage at the same time within corresponding holes such as 244, 245 formed in the assembly consisting of cradle-plate and holding-plates and within corresponding holes formed in plugs 246, 247 which are forcibly fitted in the upper extremities of the two small tubular columns 42, 43.

The two studs 242, 243 are rigidly fixed to threaded rods 251, 252 which are screwed in such manner as to be separately adjustable for height within the two extremities of a cross-member 253, the central portion of which is attached to the lower extremity of the piston rod 254 of a pressurized-fluid jack 255, the cylinder 256 of said jack being attached by means of a right-angled bracket 257 to a cross-member 258 which is in turn supported by two swan-neck members 259, the ends of the lower arms of said members being secured to two collars 261 which are clamped on the two small columns 42, 43. Two screws 264 which are mounted horizontally in the movable cross-member 253 are applied by means of their heads against two vertical

guides 265 which are attached to the upper cross-member 258.

The operation of the machine is as follows:

An incision 302 having the shape of a double "Y" has previously been formed in a bottom piece of material 301 (shown in FIG. 25) in order to form the opening of the pocket and the four edges of the opening 303 which has thus been prepared (as shown in FIGS. 26 and 27) have then been turned-in, preferably by imprisoning in the pleats a thermo-adhesive strengthening piece 304 so as to ensure permanent fastening of said turned-in edge. This preliminary preparation does not form part of the present invention and is carried out by any suitable means, whether manual or mechanical.

It is assumed that an outer pocket half-bag 307 has also been prepared beforehand (see FIGS. 28 and 30) and that a braid 311 of bottom fabric which is the same as that of the piece 301 (shown in FIG. 26) has been turned-in and stitched along the upper edge of said outer half-bag by means of two stitching lines 308, 309 and that there has also been prepared an inner pocket half-bag 314 (shown in FIGS. 29 and 31) on which there has been fixed in this example by means of a stitch 316, a pocket bottom 315 formed of the same material as the piece 301 for reasons of attractive appearance.

The outer and inner half-bags which have thus been prepared are placed in position respectively within the two drawers, namely the outer drawer 222 (shown in FIG. 19) and the inner drawer 221 (shown in FIG. 22).

In these two drawers, the pocket half-bag is clamped between the bottom portion of the drawer and the counter-plate 235 (shown in FIG. 20) or 228 (shown in FIG. 23) which is inserted in said bottom portion.

The main piece 301 is placed in position between the two hinged holding-plates 201, 208 (shown in FIG. 4), which, after having thus been loaded, are placed on the three small columns 41, 42, 43 (shown in FIG. 3). The jack 255 is supplied so as to ensure positioning and maintenance of the frame which is formed by these two holding-plates within the machine. The two loaded drawers 221, 222 are inserted between the cradle-plate 38 and the lower holding-plate 201 so that the outer drawer 222 should be advanced to the stitching position, that is to say beneath the presser foot 11 which is still uplifted, the inner drawer 221 being withdrawn to such an extent that its hole 238 (shown in FIG. 22) is in register with the hole 237 (FIG. 19) of the outer drawer, in order to ensure that the upper edge of the inner half-bag is not sewn at the same time as the outer half-bag, failing which the pocket would evidently not have any opening. In fact, fastening of the upper edges of the two pocket half-bags to the bottom material 301 is carried out in two stages. Thus, the outer half-bag is fixed in a first stage and the inner half-bag is fixed in a second stage, as will become apparent from the following description.

The presser foot 11 is lowered by supplying the jack 23 (shown in FIG. 3). The lower cradle-plate 37 takes up a position which is angularly displaced by 90° in the clockwise direction with respect to the position shown in FIG. 14 and the studs 72, 73 of the movable guide 53 (shown in FIG. 10) are engaged respectively in the holes 75C and 74C (shown in FIG. 14) of the cradle-plate. The stud 116 for coupling the sliding horizontal

guide is engaged in the hole 118C of the cradle-plate.

The sewing machine is started-up and the clutch unit 157 (shown in FIG. 17) for the reverse motion of the feed box is energized so as to make the stitch 1AR (shown in FIG. 35). At the beginning of this stitching operation, the hole 102Ca (shown in FIG. 14) of the cradle-plate 37 is located in the axis of the needle 5 and of the fork 81 (shown in FIG. 10) whereas the hole 102Cb is located in this position when this stitch has been completed.

The coupling stud 116 is released and the cradle is pivoted through an angle of 90° in the anticlockwise direction. In order to carry out this movement, the fork 81 (shown in FIG. 12) is moved upwards by means of the jack 89 (FIGS. 2 and 13). Said fork is inserted into the three holes 101Cb, 102Cb, 101Cb of the cradle-plate and lifts the guide 53 whilst the studs 72, 73 withdraw from the cradle-plate. By means of the jack 86, the fork is caused to pivot through 90° in the anticlockwise direction and then allowed to return downwards. The two studs 72, 73 of the guide engage respectively in the two holes 74A and 75A of the cradle-plate 37. The stud 116 is engaged in the hole 118A (FIG. 14) of the cradle-plate, which is located exactly in oppositely-facing relation and the stitch 2AV is performed (as shown in FIGS. 32 and 35) by engaging the forward-motion clutch unit 148 of the feed box 124. When this stitching operation is completed, the cradle is caused to pivot through 90° in the clockwise direction, the fork being inserted in the holes 101Db, 102Db, 101Db of the cradle-plate, whereupon the small stitch 3AV (FIG. 35) is carried out in forward motion, the coupling finger being transferred from the hole 118A to the hole 118D to the hole 118D and the studs 72, 73 of the guide are transferred from the holes 75C, 74C to the holes 74D, 75D.

The outer half-bag is therefore now attached to one long side and two short sides of the turned-in opening 303 of the bottom material 301 (as shown in FIGS. 32 and 35).

The lower drawer 221 of the inner half-bag (FIG. 4) is caused to advance in such manner as to bring said drawer into the position shown in FIG. 33, with the hole 239 (FIG. 22) of the inner drawer located opposite to the hole 237 (FIG. 19) of the outer drawer. In the position in which the cradle is at present located on completion of the stitch 3AV (shown in FIG. 35), the stitch 4AR (shown in FIG. 36) is carried out in reverse motion, followed immediately by the stitch 5AV in forward motion, this latter stitch being in fact superposed on the preceding stitch (as shown in FIG. 36) along one short side of the opening of which had already been provided with the stitch 3AV (FIG. 35) of the outer pocket bag.

The cradle is caused to rotate through an angle of 90° in the anticlockwise direction, the central tooth of the fork 81 (shown in FIG. 10) being located within the hole 102Da (FIG. 14) and its two lateral teeth being located within the two holes 101Da. The coupling stud 116 which was located within the hole 118D is now engaged within the hole 118B and the two studs 72, 73 of the guide are located within the holes 74B, 75B. As a result of reverse motion, the stitch 6AR (shown in FIG. 37) is made along the other long side of the opening 303 (as shown in FIG. 35).

The cradle-plate 37 is pivoted through 90° in the clockwise direction, the central tooth of the fork 81 being located within the hole 102Ca and the two lateral teeth thereof being located within the holes 101Ca. 5 When the fork returns downward, the studs 72, 73 of the guide engage within the holes 74C, 75C of the cradle-plate. The coupling stud is inserted in the hole 118C of the cradle-plate 37 (FIG. 14) and the stitch 7AR (shown in FIG. 37) is performed in reverse motion, said stitch being therefore superposed on the stitch 1AR (as shown in FIG. 35). Immediately thereafter, the stitch 8AV is made in forward motion on top of said stitch 1AR and along the small side of the opening. Fastening of the inner half-bag is completed.

The two stitches 2AV and 6AR (see also FIGS. 36 and 37) are therefore located along the two long sides of the opening 303 (as shown in FIG. 35) whereas there are located along each of the two small sides of the opening three superposed stitches (1AR, 7AR, 8AV and 3AV, 4AR and 5AV), thereby ensuring reinforcement of the ends of the opening and, at the same time and on completion of a cycle, restoring the machine to the starting condition for the following cycle.

In order to terminate the pocket, the lower edge of 25 the two lateral edges of the two pocket half-bags remain to be sewn one against the other. This operation will be carried out subsequently by any suitable means which do not form part of the present invention.

If stitching is carried out in the form of running 30 stitches as shown in FIGS. 32 to 34, the stitch will remain apparent at the location of the bottom material and will form a framed outline, as shown in FIG. 38. To this end, it is preferable to make use of a lock-stitching machine having a single needle with a flat or tubular table.

If a zig-zag sewing machine having a single needle with either a flat or tubular table is employed, the stitch will have the appearance shown in FIGS. 39 and 40 and, if care is taken to use a translucent thread or alternatively a thread having a colour which matches that of the bottom material, the seam will be practically invisible.

It is also possible to employ a zig-zag and lock-stitch 45 sewing machine which is capable of making either a zig-zag stitch or a running stitch as required.

When the seams have been completed, the needle stops automatically in the top position, the thread is cut, the presser foot is raised, both drawers 221, 222 are withdrawn, the frame is unlocked by means of the jack 255 and removed from the machine and the piece 50 301 on which the two pocket half-bags are now finally fastened is removed.

In an alternative form, feeding of the pieces of cloth 55 could be carried out in continuous motion instead of being carried out in step-by-step motion (by means of the feed box with oscillating control and free wheel in the example described above) during the period in which the needle is located at a distance from the pieces of cloth.

In the method according to the invention, in order to 60 make a button-hole having one braid, the initial operation consists in forming the button-hole opening in the bottom piece of material 331 (shown in FIG. 41) by making therein an incision 332 having the shape of a double 'Y' as shown in chain-dotted lines in FIG. 42; the four edges of the opening which has thus been prepared are turned-in as shown at 333 in full lines in FIG..

41 and in dashed lines in FIG. 42; a thermo-adhesive strengthening piece can advantageously be imprisoned in the pleats in such manner as to ensure permanent fastening of said turned-in edge. A prepared rectangular opening 334 is thus obtained in the bottom material 331. An opening having turned-in edges 337 is formed in the same manner in a facing-piece 338 (shown in FIG. 41). There is then prepared a braid 341 (FIG. 43) having dimensions which are suited to those of the openings 334 and 337 of the bottom material and of the facing-piece respectively. All these pieces being suitably superposed in the flat position, it then remains to carry out the stitching of the edge portions of the two openings between which the edge portions of the braid 341 are imprisoned, with the exception of the folded-back edge 342 of said braid, in order to permit insertion of the button within the button-hole thus obtained. This fastening operation is carried out, for example, by means of stitching lines as indicated at 343, 344 in FIG. 44. The two short sides of the opening are preferably stitched a number of times for the sake of convenience of the work in an automatic cycle on a sewing machine, which presents the advantage of strengthening the two extremities of the button-hole in a manner which is similar to the method described earlier for making braided pocket openings. The stitches can be made either in the form of zig-zag or running stitches.

The formation of a button-hole having two braids entails the successive stages which are shown in FIGS. 45 to 47 and which differ from those of FIGS. 41, 43 and 44 only in the fact that provision is made for two braids 351, 352 instead of only one.

In order to make braided button-holes, it is wholly recommended practice to make use of a sewing machine equipped with a system of the type described earlier, that is to say with a special work plate which is provided with a rectangular opening having larger dimensions than those of the button-hole to be made and beneath which is mounted a drawer for receiving and positioning the facing-piece and the braid or braids beneath the opening of the bottom piece carried by the work plate. The presser foot also has a special shape with a rectangular opening of corresponding dimensions for the insertion of the needle along the periphery of the button-hole.

There has been described in the foregoing a particular arrangement comprising a turntable for supporting the pieces to be stitched but other systems could also be used such as, for example, a system comprising a table which is capable of moving in two directions at right angles to each other as in the example illustrated in FIG. 48, in which is shown a sewing machine 361 carried by a table 362 on which a cradle 363 is capable of displacement in two perpendicular and horizontal directions X and Y. This cradle 363 is fitted with an upper plate 365 on which the bottom piece of cloth to be stitched is placed whilst a drawer which is intended for receiving and positioning the facing-piece and the braid or braids is capable of sliding beneath said cradle-plate. The presser foot 367 of open and rectangular shape is carried by a swan-neck support 368 which is rigidly fixed to the cradle 363; said foot is actuated by any suitable means, for example of the type provided in the machine which was described in the foregoing.

The principle of the machine which is illustrated is very broadly as follows: there are fixed on the table 362

two female slideways 386, 387 having a direction X in which are mounted two corresponding movable male slides 388, 389, said slides being adapted to carry a female slideway 391 having a direction Y and in which is mounted a corresponding male slide 392, the cradle 363 being fixed on top of this latter. The direction Y is perpendicular to the direction X in this form of execution.

The displacements of the cradle in the two directions 10 X and Y are carried out by means of two cams 381, 382 which are carried by a common vertical shaft 383. The can 381 actuates in opposition to a restoring spring 384, a two-arm lever 394 which is pivotally mounted on a vertical pin 395 carried by the table and which terminates in a fork 396, a stud 397 carried by the upper slide 392 being imprisoned between the arms of said fork. The can 382 actuates in opposition to a restoring spring 385 a two-arm lever 401 which is pivotally mounted on a vertical pin 402 carried by the table and which is connected by means of a pin 403 to one extremity of a link-arm 404, the other extremity of which is pivotally attached by means of a pin 405 to the upper slide 392.

In order to make a button-hole, the bottom piece of 25 material is placed on the upper cradle-plate 365, the opening of the button-hole in said bottom piece of material having previously been cut-out and turned-in as explained earlier. There are then placed in the drawer the braid or braids and the facing-piece with its opening 30 which has also been suitably cut-out and turned-in and the drawer is pushed into position, thereby automatically bringing the opening of the facing-piece and the braid or braids into a good position beneath the opening of the bottom piece of material. The sewing machine is then started-up and the suitably programmed cycle of operations automatically carries out the stitching of the contours of the opening as a result of the action of the needle and of the cams.

Any other suitable machine of conventional type 40 could be employed for the purpose of stitching the button-hole openings.

This method of execution of button-holes is not limited to pieces of textile fabric but could be applied to pieces of material in sheet form of any other type such as non-woven or knitted fabrics or even sheets of thermoplastic material.

In order to give an example of similar operations, 50 there is shown in FIG. 49 the formation of a trousers pocket having one braid and provided with a flap, the different elements of the pocket being designated by the same reference numerals as in FIG. 34, the aforesaid flap being indicated at 421; the successive operations are the same, the turned-back edge which is prepared beforehand being simply fixed at the same time as the second pocket bag 314 by means of the same stitch 64R which, in this example, is a zig-zag stitch. For the sake of convenience of assembly, the aforesaid flap 421 has preferably been attached beforehand to the facing-piece 315 and the second pocket half-bag 314 has been attached beforehand by means of a stitch 422.

FIG. 50 shows in like manner the execution of a 65 pocket having an opening with two braids and a flap. This figure differs from FIG. 49 only in the fact that it has a second braid 425 which is preferably taken beforehand in the stitch 422 for attaching the flap 421 to the second pocket half-bag 314 and to the facing-piece

315, said second braid 425 being then taken in the stitch 6AR for forming the second portion of the braided pocket opening.

It is readily apparent that the invention is not limited to the embodiments herein described with reference to the accompanying drawings and that, depending on the applications which may be contemplated, any modifications can accordingly be made therein without consequently departing either from the scope or the spirit of the invention.

What we claim is:

1. The method of making a piped opening in a garment portion, comprising the steps of:

- a. pre-forming a rectangular opening with turned-in edges in a bottom piece of material having a front face which will be exposed in the completed garment portion, and a back face opposite to said front face, 15
- b. folding a piping on itself,
- c. placing said piping and an auxiliary piece of material against said back face of said bottom piece with the edge of said piping parallel to the lengthwise edge of said opening in said bottom piece,
- d. placing a line of stitching adjacent one short end of said opening to secure said piping and the auxiliary piece to said bottom piece, 20
- e. continuing said line of stitching along one lengthwise edge of said opening,
- f. continuing said line of stitching along the other short end of said opening, all of said aforerecited lines of stitching securing said piping and said auxiliary piece along three sides of said opening in said bottom piece so that said piping cannot be pushed through the opening in said bottom piece, and 25
- g. placing a line of stitching along the other lengthwise edge of said opening to secure together said bottom piece to an auxiliary piece, all said aforerecited lines of stitching being placed while said bottom piece is permanently maintained in one and the same position, said auxiliary piece being either the aforesaid auxiliary piece, whereby a button-hole with a single braid is obtained, or a further and other auxiliary piece, whereby a pocket opening with a single braid is obtained. 30

2. A method according to claim 1, further comprising the steps of:

- a. folding a further braid or piping on itself,
- b. placing said further piping together with said auxiliary piece of material and the first piping against said back face of said bottom piece with the edge of said further piping parallel to the other lengthwise edge of said opening in said bottom piece, whereby said further piping gets secured to said other lengthwise edge of said opening and to both said short ends of said opening by said lines of stitching placed along said other lengthwise edge of said opening and adjacent both said short ends of said opening, respectively. 45

3. A method according to claim 1, characterized in that all the fastening operations aforesaid are carried out with the right side of the bottom piece, facing, upwardly.

4. A method according to claim 1, characterized in that not only the other edge aforesaid of the opening of the bottom piece is attached to the auxiliary piece but also the two extremities of said opening are attached thereto a second time.

5. The method of making a piped opening in a garment portion, comprising the steps of:

- a. pre-forming a rectangular opening with turned-in edges in a bottom piece of material having a front face which will be exposed in the completed garment portion, and a back face opposite to said front face,
- b. pre-forming a rectangular opening with turned-in edges in an auxiliary piece of material identical with said opening in said bottom piece of material to provide a facing piece,
- c. folding a braid or piping on itself,
- d. placing said piping together with said auxiliary piece of material with both openings in register against said back face of said bottom piece with the edge of said piping parallel to a lengthwise edge of said opening in said bottom piece,
- e. placing a line of stitching adjacent one short end of said opening to secure said piping and the auxiliary piece to said bottom piece,
- f. continuing said line of stitching along one lengthwise edge of said opening,
- g. continuing said line of stitching along the other short end of said opening, all of said aforesaid lines of stitching securing said piping and said auxiliary piece along three sides of said opening in said bottom piece so that said piping cannot be pushed through the opening in said bottom piece, and
- h. placing a line of stitching along the other lengthwise edge of said opening to secure together said auxiliary piece to said bottom piece, all of said aforesaid lines of stitches being placed while said bottom piece is permanently maintained in one and the same position, whereby a braided button-hole is obtained.

6. A method according to claim 5, further comprising the steps of:

- a. folding a further braid or piping on itself,
- b. placing said further piping together with the first piping and said auxiliary piece of material with both openings in register against said back face of said bottom piece with the edge of said further piping parallel to the other lengthwise edge of said opening in said bottom piece, whereby said further piping gets secured to said other lengthwise edge of said opening and to both said short ends of said opening by said lines of stitching placed along said other lengthwise edge of said opening and adjacent both said short ends of said opening, respectively, in order to obtain a button-hole having two braids.

7. The method of making a piped opening in a garment portion, comprising the steps of:

- a. pre-forming a rectangular opening with turned-in edges in a bottom piece of material having a front face which will be exposed in the completed garment portion, and a back face opposite to said front face,
- b. providing a first auxiliary piece which is an outer half-bag of a pocket,
- c. folding a piping against an edge of said first auxiliary piece,
- d. placing together said piping and said first auxiliary piece against said back face of the bottom piece with the edge of said piping parallel to a lengthwise edge to said opening in said bottom piece,

- e. placing a line of stitching adjacent one short end of said opening to secure said piping and said first auxiliary piece to said bottom piece,
  - f. continuing said line of stitching along one length-wise edge of said opening,
  - g. continuing said line of stitching along the other short end of said opening, all said afore-recited lines of stitching securing said piping and said first auxiliary piece along three sides of the opening in said bottom piece so that said piping cannot be pushed through the opening in said bottom piece,
  - h. placing a further auxiliary piece which is an inner half bag of a pocket against said piping and said first auxiliary piece, and
  - i. placing a line of stitching along the other length-wise end of said opening to secure together said bottom piece to said further auxiliary piece, all said afore-recited lines of stitching being placed while said bottom piece is permanently maintained in one and the same position, whereby a braided pocket opening is obtained.
8. A method according to claim 7, characterized in that a second braid is formed by turning-in and is also inserted beneath the bottom piece together with the

10 25

second auxiliary piece which has previously been attached to the second pocket half-bag, said second braid is attached to the other edge of the pre-formed opening by means of the same operation of attachment of the second pocket half-bag fitted with the other auxiliary piece and the two extremities of the opening are finally attached a second time in order to obtain a pocket having an opening with two braids.

9. A method according to claim 7, characterized in that said method consists in preparing a pocket flap and in attaching said flap to the other edge of the opening of the bottom piece by means of the same operation of attachment of the second pocket half-bag fitted with the other facing-piece in order to obtain finally a pocket with a flap and an opening having a single braid.

10. A method according to claim 8, characterized in that said method consists in preparing a pocket flap and in attaching said flap at the same time as the second braid to the other edge of the opening of the bottom piece by means of the same operation of attachment of the second pocket half-bag fitted with the other facing-piece in order to obtain finally a pocket with a flap and an opening having two braids.
